HINGE

Ida P. Bagley, Brooklyn, N. Y.

Application October 8, 1936, Serial No. 104,731

5 Claims. (Cl. 16—136)

This invention relates to improvements in hinges, particularly adapted for use on the heavy doors of refrigerators and similar apparatus for eliminating friction at the vertical swinging centers of the hinges.

Features of the construction may be found in ball bearings interposed between a central bearing pin having end sockets, and threaded end pins having corresponding sockets, and a sleeve enclosing the pins and balls, collectively forming a cage for the balls, said pins, balls, and sleeve being preferably of non-corrosive steel.

By reason of the ponderosity of refrigerator doors, there occurs more or less wear of the upper face of the lower bracket in hinges of this type now in general use, which causes breakage of the air seal at the door joints and a consequent escape of gas or vapors from within the refrigerator compartment. These vapors set up corrosive conditions in refrigerator hinges now in use and impair their service life.

In this invention, the above conditions cannot occur as the balls and sockets are protected from direct contact with the above described vapors by a steel sleeve welded or otherwise secured to the central bearing pin.

Another feature of the construction is a double or up and down adjustment so that the hinge may be used on left or right swing doors and further providing an upward adjustment for wear when the hinge is connected to a refrigerator door in either position.

With the foregoing and other objects in view, the invention consists in the details of construction, and in the arrangement and combination of parts to be hereinafter more fully set forth and claimed.

In describing the invention in detail, reference will be had to the accompanying drawing forming part of this application, wherein like characters denote corresponding parts in the several views, and in which—

Figure 1 illustrates a face view of my improved hinge;

Figure 2 illustrates an enlarged fragmentary section on the line 2—2 of Fig. 1;

Figure 3 illustrates a composite detail side elevation of a steel sleeve and a central bearing pin employed;

Figure 4 illustrates a face view of another form of construction;

Figure 5 illustrates a sectional view on the line 5—5 of Fig. 4; and

Figure 6 illustrates a section taken on the line 6—6 of Fig. 4.

Referring to the drawing 10 is the frame plate of the hinge and 11 is the door plate which have suitable apertures 12 through which screws or other fastenings may be passed into the frame and door of a refrigerator to secure the hinge in position.

Riveted as at 13 to a portion of the frame plate 10 is a pair of posts 14, provided with aligned threaded bores 15, through which screws 16 are secured which are locked in adjusted positions by screw or lock caps 17, at one end and their opposite ends are reduced into pins 16a, formed with ball sockets 18, to receive steel balls 19, in conjunction with opposite sockets 20, formed in opposite ends of a central bearing pin 21 having a central V cut 22 continued from a similar cut 23 formed in a preferably steel sleeve 24 extending between the posts 14 with its ends receiving the reduced pins 16a of the adjusting screws 16.

The inner side of the door plate 11 is rolled into an elongated bearing sleeve 25 which encircles the sleeve 24 and is welded or brazed thereto, as at 26, and in the brazing operation, the central bearing pin 21 and the sleeve 24 are interlocked against longitudinal strains through the V cuts 22 and 23, as will be obvious, and the central bearing pin 21 and said sleeve 24 are also brazed together within said sleeve as at 27.

The hinge shown in Figs. 4, 5 and 6 is similar to the preferred form just described, except that the steel tube 24 is eliminated and the central bearing pin 21 is brazed or welded directly to the bearing sleeve 25.

When wear takes place, the parts separate at S, Fig. 4, disclosing the fact that the refrigerator door has dropped slightly away from a completely sealed position; it is then necessary to remove the lower lock cap 17, and with a screw driver turn up lower screw 16 to cause the top of the bearing sleeve 25 to abut the upper post 14. This adjustment is required only at long intervals.

It is intended that the ball bearings run in a semi-liquid lubricant such as "vaseline" which is inserted into both ends of the sleeve or tube before the end pins are inserted into contact with the balls.

While reference has been made in this application to "steel" as the material employed in the formation of some of the elements, it is to be understood that said term comprehends any of the well known hard wear resisting metals and the applicant does not wish to be understood as confining her invention to "steel" per se.

I claim:

1. A refrigerator hinge embodying interhinged

frame and door plates provided with attaching means, posts attached in vertical alignment to the frame plate and having threaded bores, adjusting screws threaded through said bores and 5 having reduced pins terminating in ball sockets, a central bearing pin having ball cups at its opposite ends and a cross groove in its center, ball bearings confined between the opposite cups, a hard metal sleeve enclosing the pins and balls 10 and formed with a groove centrally of its length, the central bearing pin and the sleeve being connected, and said door plate having a bearing sleeve encircling said hard metal sleeve and connected to rotate therewith.

15 2. A refrigerator hinge comprising opposite frame and door plates; posts fast on the frame plate; adjusting pins threaded inwardly through the posts and having ball cups, a central bearing pin provided with ball cups in its opposite ends, 20 ball bearings in said cups, a steel sleeve surrounding the pins and balls and connected to the central pin, a bearing sleeve formed from the said door plate and connected to said steel sleeve to form a hinge joint.

25 3. A refrigerator hinge comprising frame and door plates, posts on said frame plate, and having threaded bores, adjusting screw pins extended inwardly from said bores, lock caps on said

screws, a central bearing pin, ball bearings confined between the adjacent ends of the respective pins, a bearing sleeve formed from the door plate and extending from post to post of the frame plate, a steel sleeve enclosing the pins and balls and enclosed by said bearing sleeve and means for connecting the said bearing sleeve, the steel sleeve and the central bearing pin together. 5

4. A refrigerator hinge comprising frame and door plates, opposite posts on the frame plate, pins adjustable therein, a central pin, ball bearings confined between the adjacent ends of said pins, a steel sleeve enclosing the pins and balls and extending from post to post, a bearing sleeve 10 extending from the door plate and encircling said 15 steel sleeve, and means for connecting the bearing sleeve, the steel sleeve and the central pin together.

5. A refrigerator hinge comprising frame and door plates, posts fixed to the frame plate, inwardly directed pins adjustable through said posts, lock caps on the outer ends of said pins, a central bearing pin, balls confined between the adjacent ends of said pins, a bearing sleeve 20 formed with the door plate and encircling the said 25 pins and balls, and means for connecting said sleeve to the central bearing pin.

IDA P. BAGLEY.
